(57) **CLAIM**

The ornamental design for a breathing apparatus, as shown and described.

DESCRIPTION

FIG. 1 is a front perspective view of a first embodiment of a breathing apparatus which incorporates our design.

FIG. 2 is a front view of the breathing assistance apparatus of FIG. 1.

FIG. 3 is a right side view of the breathing assistance apparatus of FIG. 1.

FIG. 4 is a rear view of the breathing assistance apparatus of FIG. 1.

FIG. 5 is a left side view of the breathing assistance apparatus of FIG. 1.

FIG. 6 is a top view of the breathing assistance apparatus of FIG. 1.

FIG. 7 is a bottom view of the breathing assistance apparatus of FIG. 1.

FIG. 8 is a front perspective view of a second embodiment of a breathing apparatus which incorporates our design.

FIG. 9 is a front view of the breathing assistance apparatus of FIG. 8.

FIG. 10 is a right side view of the breathing assistance apparatus of FIG. 8.

FIG. 11 is a rear view of the breathing assistance apparatus of FIG. 8.

FIG. 12 is a left side view of the breathing assistance apparatus of FIG. 8.

FIG. 13 is a top view of the breathing assistance apparatus of FIG. 8; and,

FIG. 14 is a bottom view of the breathing assistance apparatus of FIG. 8.
